DESIGN FOR AN ANIMAL BOOT OR SIMILAR ARTICLE

Frederick Percy Ford, Cheddar, Somerset, Albert Charles Cope, Winscombe, Somerset, and Arthur George Henry Gough, Tweentown, Cheddar, Somerset, England

Application May 5, 1936, Serial No. 62,486
In Great Britain January 10, 1936

Term of patent 7 years

To all whom it may concern:

Be it known that we, Frederick Percy Ford, a subject of the King of England residing at Station View, Wedmore Road, Cheddar, Somerset, England; Albert Charles Cope, a subject of the King of England residing at The Lawns, Winscombe, Somerset, England, and Arthur George Henry Gough, a subject of the King of England residing at The Rosery, Tweentown, Cheddar, Somerset, England, have invented a new, original, and ornamental Design for an Animal Boot or Similar Article, of which the following is a specification, reference being had to the accompanying drawing, forming a part thereof.

mal boot or similar article showing our new design.

Figure 3 is a front perspective view of the disclosure in Figure 1 but illustrating the securing flap of the animal boot or similar article in an open position; and

We claim:

The ornamental design for an animal boot or similar article, substantially as shown and described.

FREDERICK PERCY FORD.

ALBERT CHARLES COPE.

ARTHUR GEORGE HENRY GOUGH.
